UNITED STATES PATENT OFFICE.

HUDSON MAXIM, OF HOPATCONG BOROUGH, NEW JERSEY.

A-TUBE OR LINER FOR ORDNANCE.

981,095.

Specification of Letters Patent. Patented Jan. 10, 1911.

Application filed January 28, 1908. Serial No. 413,032.

To all whom it may concern:

Be it known that I, HUDSON MAXIM, of the borough of Hopatcong, county of Sussex, State of New Jersey, have invented a 5 new and useful Improvement in A-Tubes or Liners for Ordnance, which invention is fully set forth in the following specification.

The present invention relates to improvements in A tubes or liners for ordnance, 10 whereby an eroded or injured tube may be removed and replaced by another with minimum expenditure of time and money.

In carrying out the invention the gun is provided with a main tube on which the outside tubes or rings are shrunk in the usual manner. This tube is made with a uniform taper throughout its length, narrowing toward the muzzle. The A tube or liner has a corresponding taper. The outer surface 20 of the A tube and the inner surface of the main gun tube are smeared either with oil or other lubricant, preferably with a mixture of grease or paraffin or vaseline with a finely powdered metal, preferably aluminum, forming a paste. I may also, and preferably do add an admixture of graphite to the grease or mixture for the purpose. The A tube or liner is then forced into the outer or main tube of the gun with hydraulic 25 or other pressure applied to the rear end; and owing to the lubricant the liner may be forced in far enough to sufficiently compress it or put it under sufficient tension, such as has heretofore been produced by shrinking 30 on outer rings to an A tube.

Each end of the A tube or liner is preferably provided with a circumferential obturating or occluding device for retaining any excess of paste or grease between the A 40 tube or liner and the outer tube after the A tube has been forced home, which excess might otherwise be squeezed out by the discharge of the gun.

When the gun is fired the projectile in moving forward tends to rotate the inner tube with respect to the outer main tube. This is provided with an attaching means in conjunction with the obturating device at 45 both the forward and the rearward end of the A tube or liner. Furthermore, the forward pressure upon the A tube or liner, due to the thrust of the projectile along the bore, tends to thrust the A tube or liner forward yet more firmly against the outer or main tube of the gun, and this serves both to prevent the turning of the A tube or liner, and

further tends to compress it and throw the main tangential strain upon the outer or main tube and the main body of the gun.

When the A tube or liner has been worn 60 out, eroded, or damaged, it is only necessary to remove the obturating and attaching means at its forward and rearward ends and force it out with hydraulic pressure, in the reverse direction to that which forced it 65 into place. However, the A tube or liner is provided with one or more grooves or cannelures extending preferably in a spiral direction along its outer surface from rear to front; and means are provided by which oil 70 or other fluid may be forced under hydraulic pressure into the said cannelures or grooves, which will serve to compress and collapse the inner tube and thereby enable it to be very readily withdrawn from the gun without 75 having to be drawn out with the exercise of great force or pressure.

So simple is this invention in its practical operation that all of the necessary apparatus and paraphernalia for the removing 80 and replacing of the A tubes and liners of large guns may be carried and the work very readily effected on battleships and within forts without returning the guns to factories or arsenals for the purpose. As the 85 A tube or liner is relatively long for its diameter and thickness, and somewhat flexible, a strong and heavy tube is provided and adapted to receive the A tube or liner and hold it firmly and rigidly while boring out 90 and rifling it.

The accompanying drawings illustrate a practical embodiment of the invention, in which drawings:

Figures 1 and 1^a, are together a longitudinal section of the greater portion of a cannon. Fig. 2 is an elevation of the breech portion of the A tube or liner. Fig. 3 is an enlarged longitudinal section of the A tube or liner at the breech end, and Fig. 4 95 is a cross section of the same on the line 4, 4, of Fig. 3. Fig. 5 is an enlarged section of a portion of the muzzle end of the cannon.

Referring to said drawings, the cannon B 105 of the usual built-up construction is provided with the improved A tube or liner 10, firmly seated within a main tube 12. At the breech end the A tube is formed with a flange or head 11, carrying on its forward face an annular V-shaped projection 9, co-acting with an opposed recess 8, formed in

the rear shoulder of the main tube 12, between which is confined an obturating ring of any well known form, a copper ring or a de Bange ring, as desired, to close the rearward end of the joint between the liner and main tube. The muzzle end of the **A** tube or liner 10, is held against material longitudinal displacement by a stop-annulus 14, fitting over a slightly reduced end portion of the **A** tube and screw threaded to the main tube 12, the inner end of the annulus being firmly seated against a packing ring or other obturating device 7, to close the forward end of the joint between the liner and main tube and effectually occlude the escape of lubricant.

The outer surface of the **A** tube or liner 10, is one continuous long taper from its flange or head 11 to the reduced end portion 20 of the muzzle and fits a correspondingly tapered inner surface of the main tube. The outer surface of the **A** tube is formed with channels or grooves 2, extending circumferentially and spirally from a single 25 annular channel 3, at the breech end to a point near the muzzle within which to force a suitable lubricant or a mixture of a lubricant and a powdered metal, as before described. Access to these channels or grooves 30 after the **A** tube or liner is in place in the gun may be had by drilling out a continuation of a short longitudinal hole 5, in the head or flange of the liner, as seen in Fig. 3.

What is claimed is:

- 35 1. In combination, a main gun tube and an **A**-tube or liner having walls with uniform taper adapted to fit said gun tube, said **A**-tube having grooves in its exterior surface for holding lubricant and for receiving fluid 40 under pressure to collapse said tube and facilitate its removal from the gun tube.
2. In combination, a main gun tube and an **A**-tube or liner having walls with a uniform taper adapted to fit said gun tube,

said liner having grooves in its exterior surface for holding lubricant and for receiving fluid under pressure to collapse said tube to facilitate its removal from the gun tube, and obturating means preventing escape of lubricant from between the liner 50 and said main gun tube.

3. In combination, a main gun tube and an **A**-tube or liner adapted to fit said main tube, one of said tubes having grooves on its surface for holding lubricant between 55 said tubes and for receiving fluid under pressure to collapse said tube and facilitate its removal from the gun tube.

4. The combination of a main tube, a liner having at the breech end a flange opposed to a shoulder on the main tube and a stop-annulus screwed to the main tube and mounted on a reduced portion of the liner at the muzzle end.

5. In combination, a main gun tube and 65 an **A**-tube or liner having one or more longitudinally extending lubricant channels in one of said tubes, a circumferential distributing channel at or near one end of the **A**-tube opening into said first named channel, and 70 obturating means for preventing escape of lubricant from between said tubes.

6. In combination, a main gun tube and an **A**-tube or liner having one or more grooves longitudinally arranged in its exterior surface for receiving lubricant, a distributing groove near one end of said liner opening into said first named grooves and obturating means preventing escape of lubricant from between the liner and said 80 main gun tube.

In testimony whereof I have signed this specification in the presence of two subscribing witnesses.

HUDSON MAXIM.
